UNITED STATES PATENT OFFICE.

SAMUEL N. ETTINGER, OF DORCHESTER, MASSACHUSETTS.

GARMENT.

1,159,369.

Specification of Letters Patent.

Patented Nov. 9, 1915.

Application filed March 6, 1913. Serial No. 752,310.

To all whom it may concern:

Be it known that I, SAMUEL N. ETTINGER, a citizen of the United States, and a resident of Dorchester, in the county of Suffolk and 5 Commonwealth of Massachusetts, have invented an Improvement in Garments, of which the following description, in connection with the accompanying drawings, is a specification, like characters on the drawings 10 representing like parts.

This invention relates to garments, and more particularly to the art of making the sleeves thereof.

Heretofore, in making sleeves, considerable difficulty has been experienced in providing sleeves of the correct length. In a ready made coat the sleeves are apt to be either too long or too short to suit the wearer and even in coats which are made to order 15 it is frequently found necessary to lengthen or shorten one or the other of the sleeves. This adjusting of the end of the sleeve is of considerable inconvenience since it is necessary to rip open seams and turn in or let 20 out the sleeves and then sew the seams together again.

The principal object of the invention is to provide a sleeve construction whereby the 25 length of the sleeves may be readily lengthened and shortened without inconvenience.

The character of the invention may be best understood by reference to the following description of an illustrative embodiment thereof shown in the accompanying 30 drawing, wherein:

Figure 1 is a side view of a sleeve typifying prior constructions; Fig. 2 is a side view of an illustrative sleeve shown herein as embodying the invention, a portion of the 35 sleeve being broken away to disclose the construction thereof; and Fig. 3 is a view similar to Fig. 2, showing the sleeve extended as more fully hereinafter described.

Referring to the drawing, in Fig. 1 is 40 shown a sleeve constructed as heretofore has been the practice, and which comprises a body portion 1, a lining 3, and a filler 5 of thin canvas or other suitable material extending to the edge of the cuff. The end 45 portion of the sleeve is turned in as at 7, and the lining is carried down to overlap this end portion to a substantial extent and the edge of the lining is turned under as at 9 and stitched to said portion to form a finished seam. This seam is located a substantial 50 distance in from the edge of the cuff

in order that the lining may not be readily visible through the end of the sleeve. If it is desired to change the length of the sleeve it is necessary, for example to shorten 60 the sleeve, first to rip open the seam 9, then cut off or fold in the end of the lining, fold in the inturned portion 7 farther and then stitch the lining to this turned-in portion. The sleeve is then pressed to destroy the 65 wrinkle formed by the previous edge of the cuff. All of this requires considerable inconvenience and labor.

Referring now to Figs. 2 and 3, there is shown an illustrative sleeve embodying my 70 invention which may be readily lengthened or shortened with none of the objections above referred to. This sleeve comprises a body portion 11, a lining 13 and a stiffening filler 15. The lining is extended down 75 substantially to the edge of the cuff and the edge portions of the outer fabric of the sleeve and the lining are turned in and sewed together to form a finished seam 17. The stiffening filler 15 preferably is carried 80 down and terminates at the edge of the cuff. The end portion of the cuff thus formed, including the outer fabric, the lining, and the filler, are together turned in to form an adjustable internal cuff 19, as shown 85 in Fig. 2. The sleeve is of a sufficient length to permit the turning in of this cuff a substantial distance to provide the desired extent of fabric from the edge of the cuff to prevent the lining from becoming readily 90 visible. The edge of the cuff is then pressed 95 to form a firm crease presenting a well defined edge, and the sleeve is complete. The sleeve is made somewhat longer than the usual sleeve in order that it may be adjusted to conform to the length of the arm of the wearer as desired.

If the sleeve be too long to fit the wearer the internal cuff is pulled out and the sleeve is pressed to eliminate the wrinkle formed 100 by the former edge of the sleeve. The sleeve cuff is then turned in a proper amount to cause the edge to conform to the arm of the wearer. The sleeve is then pressed as before to present a firm, well defined, finished edge. Similarly, if the sleeve be too short, the cuff is pulled out as before and then turned in the proper distance and pressed. Thus the sleeve is readily adjustable 105 to provide the proper length for the arm of the wearer without the necessity of the ripping open of any seams and the re-

stitching thereof; but, on the contrary, by the simple turning in and pressing of the internal cuff the sleeve may be given any length desired.

- 5 Where the sleeve is applied to a ready made coat it may be placed in the sales room without turning in the cuff in the form shown in Fig. 3. When the coat is sold the cuff may be turned in the proper 10 amount to fit the wearer and the edge pressed. By this simple operation the sleeve is adjusted to the length desired. In some cases to prevent inadvertent pulling out of the cuff, as when the arm is inserted in the 15 sleeve, its inner free end may be caught at diametrically opposed points to the lining of the sleeve, or said end may be basted thereto by stitching as desired, although this is not indispensable.
- 20 Having described one illustrative embodiment of the invention, without limiting the same thereto, what I claim as new and desire to secure by Letters Patent is:

A ready-made sleeve having a turned-in

cuff of variable length; said sleeve comprising an outer fabric and a lining of equal lengths, and permanently sewed together at the outer end of the sleeve, said outer fabric and lining being extended beyond the normal length of the sleeve to form an adjustable sleeve-shortening-and-lengthening cuff, said lining being continuous from the lower end of the sleeve to the upper end thereof, and attached only at the extreme lower end of the sleeve, and being free from the outer fabric of the sleeve from said lower end upwardly, whereby the material may be folded inwardly to form a cuff and whereby the said lining lies wholly between both layers of the sleeve material.

In testimony whereof, I have signed my name to this specification, in the presence of two subscribing witnesses.

SAMUEL N. ETTINGER.
